UNITED STATES PATENT OFFICE.

JOHN H. ORMSBY, OF BOLTON LANDING, NEW YORK.

DOOR-KNOB FASTENING.

SPECIFICATION forming part of Letters Patent No. 470,072, dated March 1, 1892.

Application filed September 30, 1891. Serial No. 407,348. (No model.)

To all whom it may concern:

Be it known that I, JOHN H. ORMSBY, a citizen of the United States, and a resident of Bolton Landing, in the county of Warren and

5 State of New York, have invented certain new and useful Improvements in Door-Knob Fastenings; and I do declare the following to be a full, clear, and exact description of the invention, such as will enable others skilled 10 in the art to which it appertains to make and use the same, reference being had to the accompanying drawings, and to letters of reference marked thereon, which form a part of this specification.

15 Figure 1 of the drawings is a vertical longitudinal section. Fig. 2 is a view of the knob-plate, the parts being detached.

This invention has relation to means for fastening door-knobs to spindles; and it consists 20 in the novel construction and combination of parts, as hereinafter described.

In the accompanying drawings, the letter A designates a knob having the inner end of its shank portion B provided with a shoulder 25 or flange a. Said shank also has an angular aperture b, which receives the end of the spindle or bar C.

D is the knob-plate fitting around said spindle and having therein a groove d to receive 30 the shoulder or flange a of the knob-shank. This plate is formed in two pieces D' and D² to permit it to be slipped over and

into engagement with the shoulder a after the knob is applied to the door. The section D² is preferably wedge-shape, fitting closely into 35 section D'. Said sections are held in place by screws f.

It will be seen that by this construction I obviate the use of the screw ordinarily used for connection between the knob and the spindle and which is liable to become loose and lost.

Having described this invention, what I claim as new, and desire to secure by Letters Patent, is—

45 The combination, with a door-knob having the inner end of its shank formed with a broad flange or shoulder and its end plate angularly chambered to receive the spindle, of the door-plate secured to the door in the ordinary manner and having a central perforation to receive the knob-shank, the inner face of said plate having a groove d around said perforation to receive the said shoulder or flange and formed in two sections, the 50 smaller wedge-shaped section being removable, substantially as specified.

In testimony whereof I affix my signature in presence of two witnesses.

JOHN H. ORMSBY.
